UNITED STATES PATENT OFFICE

2,094,176

CLOTH SPREADER

George N. Kumbera, University City, Mo.

Application April 20, 1936, Serial No. 75,395

5 Claims. (Cl. 270—31)

This invention relates to a certain new and useful improvement in what may be descriptively designated cloth-spreaders.

In the manufacture of wearing-apparel garments and the like, economy in cost of production follows from a simultaneous or multiple cutting at a single operation and from a single pattern of a plurality of like sections, and my present invention has for its chief object the provision of 10 means in the form of a structure adapted for movement back and forth or reciprocatorily over a work-table for mechanically rapidly unwinding a roll of cloth, fabric, or the like and spreading the unwound cloth upon the table uniformly and 15 evenly in the desired number of superposed plies or layers convenient for simultaneous pattern-cutting.

And with the above and other objects in view, my invention resides in the unique features of 20 form, construction, arrangement, and combination of parts presently described and pointed out in the claims.

In the accompanying drawing,

Figure 1 is a side elevational view of a cloth-spreader constructed in accordance with and embodying my invention; and

Figures 2 and 3 are opposite end views of the cloth-spreader.

Referring now more in detail and by reference 30 characters to the drawing, which illustrates a preferred embodiment of my invention, the structure, which I have designated a spreader, includes a carriage A constructed for movement over and upon a work-table T, the carriage A, 35 in turn, comprising a pair of end-frames 1, 2, each substantially of A-shape or so-called inverted V-shape rigidly secured together in suitably spaced, parallel relation by cross-bars 3 and interposed tubular sleeves 4. For ease and 40 convenience of travel, one end-frame, as frame 1, is suitably equipped with rollers or wheels 5 in tandem relation for movement on the table T and the other end-frame, as frame 2, is suitably equipped with circumferentially grooved pulleys 45 or wheels 6 similarly in tandem relation for spreader-guiding movement on a rail 7 provided longitudinally along a margin of the table T, all as best seen in Figure 1.

Removably journaled for rotation upon the 50 bight or body of the end-frames 1, 2, for supporting the cloth-roll R to be unwound and spread, is a shaft 8, shiftably disposed on which for properly centering the roll R in the carriage A, are disks or the like 9, whose respective hubs 9' 55 are each equipped with a set-screw 10 engage-

able with shaft 8 for retaining the disks 9 in adjusted or shifted position.

The respective legs a, b, of the carriage end-frames 1, 2, are longitudinally slotted in registration, as at 11, 11, to shiftably accommodate 5 the end-portions of respective shafts or bars 12, 12, suitably mounted lengthwise upon which for rotation are suitably elongated guide-rollers 13, 13.

Accordingly, in use and operation, the roll R 10 of cloth, fabric, or the like to be unwound and spread upon the table T in superposed layers for convenient multiple cutting operations in the economical simultaneous manufacture of a plurality of garments, as I have described, is disposed and centered by the disks 9 on the shaft 8, the free end-portion r of the roll R being brought down and under a respective roller 13 and end-wise temporarily retained, as by means of a suitable weight or the like, not shown, on the table 20 T. The carriage A is then moved a desired distance in one direction over the table and a portion of the roll R is thereby disposed, as at r', in a layer or flatwise, as I may say, on the table T. Travel of the carriage A is then reversed, the so 25 disposed cloth layer r' being also retained end-wise on the table by a second weight or the like, as at 14, and as the carriage A is thus caused to reversely travel, the unwinding end-portion of roll R shifts to and under the opposite roller 13, 30 and a second or superposed layer r'' is disposed on and over the first layer r', and so on until the roll R has been completely unwound and disposed in, as described, superposed layers on 35 the table T, the rollers 13 and their supporting shafts 12 being readily adjustable to meet spreading requirements as the roll R gradually becomes reduced in diametrical dimensions.

To retain the roll-supporting shaft 8 from excessive rotative speed during travel of the carriage A, the one frame, as frame 2, is equipped with a laterally extending flange or shelf 15, threaded in which for adjustment is a screw or the like 16 carrying for shaft engagement a suitably lined brake-shoe 17, the carriage A being 45 also preferably provided with hand-grips 18 for carriage-shifting manipulation.

The spreader may be inexpensively constructed, is facile in use and operation, and is efficient in 50 the performance of its intended functions.

And it is to be understood that changes and modifications in the form, construction, arrangement, and combination in the various parts of the spreader may be made and substituted for those herein shown and described without depart- 55

ing from the nature and principle of my invention.

Having thus described my invention, what I claim and desire to secure by Letters Patent is,—

- 5 1. In a cloth-spreader, in combination, a carriage comprising a pair of spaced parallel end-frames of A-structure adapted for movement over a work-table, a roll-supporting shaft journalled for rotation on said frames between the apices of said A shaped end-frames, and rollers mounted for adjustment on the legs substantially upwardly and away from the plane of the work-table for alternate engagement with the unwinding cloth as the carriage is caused to travel reciprocatorily over the table for guiding the cloth toward the table.
- 10 2. In a cloth-spreader, a carriage comprising a pair of spaced parallel end-frames of A-structure adapted for movement over a work-table, a roll-supporting shaft journalled for rotation on said frames between the apices of said A shaped end-frames, the legs of said frames being longitudinally slotted in registration, and rollers mounted on said legs substantially upwardly and 15 away from the plane of the work-table for alternate engagement with the unwinding cloth as the carriage is caused to travel reciprocatorily over the table for guiding the cloth toward the table, said rollers having their end-portions disposed for adjustment in said slots.
- 20 3. A cloth-spreader comprising a pair of similarly shaped inverted V frames, aligned journals formed in the vertices of the frames for receiving a removable cloth-supporting spindle, adjustable brake means mounted in one of the frames for braking engagement with the spindle when the latter is in operative position in the journals, a pair of rods extending between the legs of the frames for holding the latter in rigid parallel 25 alignment, and freely rotating rollers mounted on the rods, said rods and associated rollers being positioned upwardly and away from the plane of 30

the leg-bottoms of the frames for providing an entirely free space through which the cloth may freely drop foldwise upon itself as the course of travel of the cloth-spreader is reversed.

4. A cloth-spreader comprising a pair of similarly shaped inverted V frames, aligned journals formed in the vertices of the frames for receiving a removable cloth-supporting spindle, adjustable brake means mounted in one of the frames for braking engagement with the spindle when the latter is in operative position in the journals, a pair of rods extending between the legs of the frames for holding the latter in rigid parallel alignment, and freely rotating rollers mounted on the rods, said rods being spaced from each other horizontally a distance approximately equal to the distance of the rods above the plane of the leg-bottoms of the frame, for providing an entirely free space through which the cloth may freely drop foldwise upon itself as the course of travel of the cloth-spreader is reversed.

5. A cloth-spreader adapted for cloth-spreading travel to and fro over a work-table comprising a pair of upstanding opposed end frames, each of said end frames being provided with a pair of downwardly and outwardly diverging leg members, a cloth-supporting spindle mounted at its extremities for rotatable movement in and extending transversely between the upper portions of the end frames, and a pair of parallel cloth-engaging rollers, each of said rollers being mounted at its extremities in and extending transversely between opposed leg members of the end frames respectively, said rollers being spaced laterally from each other and substantially upwardly from the plane of the work-table for providing an entirely free space therebetween through which the cloth may freely drop foldwise upon itself as the course of travel of the cloth-spreader is reversed.

GEORGE N. KUMBERA.
